BACK BRUSH

Leidy G. Scholl, Lansdale, Pa.

Application September 28, 1956, Serial No. 43,145

Term of patent 14 years

(Cl. D9—2)

Figure 5 is a fragmentary top plan view of my design showing a portion of the removable handle in an alternate position.

I claim:

The ornamental design for a back brush, as shown.
